UNITED STATES PATENT OFFICE.

ARTHUR O. HIGINBOTHAM, OF DENVER, COLORADO, ASSIGNOR OF ONE-HALF TO WILLIAM A. WEIGELE, OF DENVER, COLORADO.

METHOD FOR SUPPLYING OXYGEN TO COMBUSTION CHAMBERS.

Original application filed August 15, 1924, Serial No. 732,323. Divided and this application filed July 11, 1925. Serial No. 43,043.

This invention relates to an improved method of admitting oxygen to the fire bed of a boiler or furnace after firing, whereby to prevent the formation of excessive smoke by a substantially complete combustion of the gases emanated from the burning fuel, and it is an object of the invention to produce this result by the automatically controlled admission of oxygen to the fire chamber at a predetermined rate.

A further object of the invention is to effect the practically complete combustion of every heat producing element of the fuel by a gradual admission of oxygen to the fire bed during a predetermined period of time.

An apparatus capable of carrying the improved method of oxidation into practice has been illustrated in the accompanying drawings, said apparatus having been more fully disclosed in my application for patent No. 732,323, filed August 15, 1924, of which the present application is a division.

In the drawings in the several views of which like parts have been similarly designated,

Figure 1 represents a front view of a portion of a furnace wall and a door closing the fire-opening thereof, in association with mechanism for admitting oxygen to the fire-chamber of the furnace by a time controlled movement of a damper on the door, automatically produced when the door is closed after each replenishment of the fire. In this connection, it is to be understood that while my invention as illustrated in the drawings, is particularly adapted for operation by movement of the furnace door, its objects may also be attained by medium of a hand-actuated mechanism or through the instrumentality of a moving part of a furnace, other than the fire-door, as for example, the reciprocating piston-ram of a mechanical push stoker;

Figure 2 is an enlarged vertical section along the line 2—2, Figure 1;

Figure 3, a vertical section taken on the line 3—3, Figure 1; and

Figure 4, a section in a vertical plane designated by the line 4—4, in Figure 1.

The elements of the mechanism illustrated in the drawings, co-operatively assembled in association with the hinged fire-door 5 of a furnace 6, are a pair of dampers 7 normally closing a rectangular opening in the

door through which in practice, air is admitted to the fire in the combustion chamber of the boiler, a rotary cam 8 which operates the dampers, and a time-mechanism 9 of the escapement type operatively connected with the cam.

The dampers in their closed position overlap one another to completely cover the air-opening of the door inside of an outwardly projecting flange 10 and they are hung upon the flange for pivotal movement about horizontal axes by means of shafts 12.

The shafts are provided at one of their ends projecting exteriorly of the flange, with crank-arms 13 and 14 connected by a bar 15 for conjoint movement and the upper crank arm 13 carries upon an elongated wrist-rod 16, an anti-friction wheel 17 which bears upon the peripheral edge of the cam.

The cam-element in its simplest form consists of a disk having a peripherally grooved edge of irregular form, but it is preferably composed of a number of steps of corresponding outlines but progressively decreasing diameters to vary the extent to which the dampers may be opened by rotation of the cam-element.

The anti-friction wheel 17 is to this end slidably mounted on the wrist rod 16 of the cam so that it may be adjusted from one step of the cam element to another across the entire width thereof.

The cam is fixed at an end of a shaft 18 supported for rotation in openings of the rectangular flange 10 around the door-opening and connected at its opposite extremity 90 with the gear-train of the time-mechanism, contained in a housing 19 which is secured upon the door at a side of the flange opposite to the cam-element.

The time-mechanism is operated by a coiled spring 20 disposed between a shoulder 21 on an oscillating lever 22 operatively connected with the drive wheel 34 of the mechanism, and a thereto opposed shoulder 23 on a bell crank 24 which is mounted to rock 100 in bearings at the lower portion of the door. The lever 22 is loosely mounted on the shaft of the drive wheel 34 and its operative connection with the latter is established by the medium of a pawl, hereinafter to be described.

A rod 25 fastened on the lever and extending loosely through an opening of the

shoulder on the bell crank, passes through the spring to prevent its lateral deflection.

A pin 26 on the arm of the bell crank opposite to that engaged by the spring, 5 passes loosely through an opening in the door to engage the frame of the boiler around the fire-opening, when the door is in the closed position.

The connection between the lever and the 10 time-movement is established by means of a pivoted pawl 27 which normally engages with a notched wheel 28 at the end of the spindle of the drive wheel of the movement, upon which the lever is supported.

15 Lugs 29 and 30 on the housing of the time-mechanism limit the arcuate movement of the lever as will hereinafter be more fully explained.

The time-mechanism is controlled by an 20 adjustable escapement 31 of suitable construction. A simple and practical form of escapement, shown in the drawings, consists of a vertical oscillatory shaft 32 which carries at its upper end two simultaneously 25 adjustable opposed weights 33. By varying the distance of these weights from the axis of oscillation of the shaft, the velocity of the time-mechanism may be accurately regulated.

30 When the fire-door is in its normal closed position, its air-opening is tightly closed by the lapping dampers and the time-mechanism is in a condition of inactivity owing to the expanded condition of the spring.

35 The anti-friction wheel on the crank-arm of the upper damper is placed in one of the grooved steps of the cam, according to the extent to which the dampers are to be opened during the predetermined time period, and 40 the pawl on the lever is engaged in one of the notches of the wheel 28 on the shaft of the drive wheel on the time-mechanism.

In case it is desired to close the fire-door 45 without actuation of the damper-operating time-mechanism, the pawl is disengaged from the wheel as shown in broken lines in Figure 2.

When the fire-door is opened for the purpose of replenishing the fire in the combustion chamber of the furnace, the pin 26 on the bell crank lever 24 is projected through the opening of the door by gravity of the parts with which the lever is associated and the lever 22 is by the same influence moved 55 to the position shown in Figure 2. The opening through which the pin passes is sufficiently large to permit of the slight lateral displacement of the pin caused by the arcuate movement of the end of the bell crank arm.

60 When, after the fire has been coaled, the door is returned to its closed position, the pin by contact with the furnace wall, compels the bell crank to move about its axis 65 and the corresponding movement of the

shoulder 23 compresses the spring against the opposed shoulder of the lever 22 which is held through the medium of the pawl 27 by the frictional resistance of the time-mechanism of which it is a part. The upper arm of the bell crank extends at this point in the operation, at an acute angle to a perpendicular passing through its pivotal axis, thereby compelling the spring to exert the force of its expansive movement upon the lever 22 and reducing the tendency of the spring to open the fire door by a reverse movement of the bell crank, to the minimum.

The expansion of the spring causes the 70 time-mechanism to operate through engagement of the pawl 27 with the notched wheel 28 until the lever 22 engages the stop 30 when its movement is automatically discontinued.

The movement of the mechanism and the 75 rate of consequent rotation of the cam shaft 18, are controlled by the adjustable escapement, which thereby predetermines the time period during which the dampers are opened 80 and closed and regulates the operation according to variable circumstances, such as the kind of fuel supplied to the furnace or the quantity of fuel fed into the fire chamber of the furnace at one time.

The rotary motion of the shaft 18 is, 85 through the medium of the cam, converted into a gradual opening movement of the dampers to an extent determined by the peripheral shape of the step of the cam with 90 which the wheel on the crank-arm of the upper damper is in contact. Thus, when the cam rotates in the direction of the arrow C in Figure 4, the dampers are gradually opened by upward movement of the wheel 17 until the latter passes the point of greatest diameter of the cam when the wheel is 95 lowered under the influence of its own weight and that of the other members of the movement with which it is associated, 100 until the dampers are again in the closed position.

The duration of the damper movement is 105 determined by the rate of operation of the time-mechanism under control of its escapement governor and by moving the contact wheel from one step of the cam to another, or by interchanging the cam with another of different shape, the proportionate lengths of the gradual opening and closing movements of the dampers may be varied.

The extent to which the dampers are 110 opened during the time period predetermined as stated hereinabove is measured by the diameter of the cam, and thus may likewise be varied by adjustment of the contact wheel or by the use of different cams as hereinbefore explained.

The air entering the combustion chamber 115 of the furnace past the gradually opening 120

dampers, may be preheated and diffused by contact with suitably constructed baffle plates disposed in the opening of the door as indicated at 35 in Figure 3, and by proper regulation of the movement of the dampers as hereinbefore described, the air supply may be varied according to the requirements of the fuel, to form a substantially perfect combustible mixture with the gases arising from

10 the burning fuel, and thereby prevent the formation of smoke.

Having thus described my invention what I claim and desire to secure by Letters Patent is:

15 1. The method of oxidizing gases evolved from fuel in a combustion chamber, consisting in automatically supplying air directly to the chamber in a gradually increasing quantity during a predetermined period of

20 time.

2. The method of oxidizing gases evolved from fuel in a combustion chamber, consisting in automatically supplying air directly to the chamber in a gradually increasing 25 and subsequently gradually decreasing quantity during a predetermined period of time.

3. The method of oxidizing gases evolved

from fuel in a combustion chamber having a fire door, consisting in closing the fire door after the fire has been replenished, supplying 30 air directly to the replenished fire in the chamber in an increasing quantity to a predetermined peak, maintaining the supply of air at the peak for a predetermined period of time, and then decreasing the quantity to 35 zero.

4. The method of oxidizing gases evolved from fuel in a combustion chamber, consisting in automatically supplying air directly to the chamber in an increasing quantity, 40 continuing the maximum supply of air during a predetermined period of time, and then decreasing the quantity.

5. The method of oxidizing gases evolved from fuel in a combustion chamber, consisting in the introduction of air directly into the chamber shortly after charging the same, in a gradually increasing quantity to a given 45 peak and then decreasing said quantity to zero.

In testimony whereof I have affixed my signature.

ARTHUR O. HIGINBOTHAM.
